UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

STEAM-HEATING SYSTEM.

1,164,807.

Specification of Letters Patent. Patented Dec. 21, 1915.

Original application filed November 7, 1911, Serial No. 658,985. Divided and this application filed January 3, 1912. Serial No. 669,271.

To all whom it may concern:

Be it known that I, EDWARD E. GOLD, a citizen of the United States, residing in the borough of Manhattan, city, county, and State of New York, have invented certain new and useful Improvements in Steam-Heating Systems, of which the following is a specification.

My invention relates to steam heating systems and is particularly applicable to heating systems for use in heating cars of railway trains. It is a division of my application filed November 7, 1911, Serial No. 658,985.

15 An important object of the invention is to reduce the weight of the heating system installed in the car. Such heating system is maintained in the car throughout the entire year, and during a considerable part 20 of the year it is not required for heating the car. But during all of this time it must be transported with the car as dead weight. The weight of such system whether in use or not furnishes a large addition to the 25 weight of the car, and its transportation is a subject of considerable expense to the railway companies.

My invention therefore aims to reduce the weight of such steam heating system, 30 and this I attain by a construction wherein a duplication of parts is avoided, and consequently the weight of the apparatus of the heating system is much lightened.

An object of my invention is also to provide a steam heating system wherein the supply of heat radiated may be decreased by reducing the extent of radiators in use and thereby reducing the consumption of steam.

40 A further object is to provide that when any radiator or radiators are so unused, there will be no back-flow of steam thereto. Further, to provide means controlled in common by said radiating systems when 45 acting as vapor systems for shutting off the steam supply.

In carrying my invention into effect I provide a plurality of radiating systems in the car, either of which may be disconnected independently of the others, and which combined or singly are adapted to be operated as either pressure or vapor systems; and I provide means whereby when

such plurality of radiating systems are operated as vapor systems they are subject 55 to a common control. In accordance with my invention a common supply pipe is provided having an inlet valve, and each radiating system has an independent return pipe. Each return pipe is adapted by adjustment to exhaust through its independent trap when operating as a pressure system, or by adjustment when operating as a vapor system all of said return pipes may exhaust through a common outlet, connected with which are thermostatic means controlled by the temperature in the said outlet for automatically operating the valve in the supply pipe.

A desirable form in which my invention may be embodied is illustrated in the accompanying drawings.

In the said drawings.—Figure 1 is a plan view of a steam heating system according to my invention, partly broken, the parts beneath the floor of the car being shown in dotted lines; Fig. 2 is a cross-section thereof on the line 2—2 in Fig. 1 looking toward the right; Fig. 3 is a view partly in elevation and partly in section of a common valve employed with said invention; Fig. 4 is a further view of said valve and its connections partly in plan and partly in section; Fig. 5 is a view of the said valve partly in plan and partly in section on the line 5—5 in Fig. 4; Fig. 6 is a view of the parts of the steam heating system below the car floor taken on the line 6—6 in Fig. 2, illustrating the said parts partly in plan and partly in section. Fig. 7 is a perspective view of a heating system having a different arrangement of radiators.

I have illustrated my invention as applied to a steam heating system wherein steam is supplied to the radiating systems 95 located within the various cars from the train-pipe A which extends the length of the train, and is supplied with steam from the locomotive boiler. Branches A' are connected to the said supply pipe and conduct steam therefrom to the supply pipe B which supplies steam to the radiating systems C C' located within the car. Each of the said systems has a hand-controlled valve c by which steam may be shut off from any one 100 of the said systems. As illustrated in Fig.

1, each car contains four of such steam heating systems, each of which may be operated independently of the others, and they are illustrated as being divided so that two of 5 such radiating systems are located upon each side of the car. Each of such radiating systems is illustrated as double branched, having branches c^1 c^2 each of which has a lower return pipe c^3 c^4 . The 10 employment of the double branched radiating pipe is not essential to my invention and the said radiating pipe would be equally within my invention if a single steam pipe c^5 and connected single return pipe c^6 were 15 used (Fig. 7). The extent of radiating surface may be increased when desired by the employment of such double branched radiators or by lateral branches H , as in Fig. 7, or by lateral loops illustrated in Fig. 1 20 and not lettered. Other means may also be employed to increase the radiating surface, as for instance the coiled wire h^3 (Fig. 1). My invention however is not concerned with such lateral branches or loops 25 or wire coils and they form no part thereof. The return pipes c^3 c^4 are each connected to return pipes J J^1 which extend beneath the floor of the car and are there connected to a valve K . The said valve is illustrated 30 in Figs. 3, 4 and 5. It is provided with passages k^1 k^2 (Fig. 4) which extend from the said return pipes J J^1 to screened pipes l leading to traps L . The said traps L are ordinary thermostatically controlled T-traps 35 for disposing of the condensation water, and their construction forms no part of the present invention. Gravity traps M may well be situated in communication with each of the said passages k^1 k^2 . The valve K is 40 provided with a central bore in which slides the valve proper k^3 controlled by a handle k^4 or by its usual extension handle k^5 . Ports k^6 k^7 connect the passages k^1 k^2 with said central bore when the valve k^3 is raised. 45 It will be seen from the foregoing that when the valve k^3 is closed and the steam escapes through the passages k^1 k^2 of the valve K and through the T-traps L , that the return pipes are entirely disconnected from 50 each other and are independent in their operation. Each T-trap contains a thermostatic vessel l^1 which is partly filled with a volatile fluid usually employed for that purpose, such as alcohol, etc., and is adapted to 55 expand when steam passes through the return pipe, and seat itself against the seat l^2 , closing the pipe l . When the condensed water collects and cools the thermostat it will contract and withdraw from seat l^2 under influence of spring l^3 and the pipe l will 60 then be open and permit the escape of the condensed water. The systems will then operate as pressure systems.

65 The following means may be provided when it is desired that the system should be

operated as a vapor system:—The valve K is provided with a blow-off k^8 communicating with the central bore when the valve k^3 is raised and which when the system is operating as a pressure system, is closed by the 70 valve k^3 . This outlet communicates with a drip pipe or horn N , Fig. 5, which is open to the atmosphere at its lower end. When it is desired that the system operate as a vapor system this drip is provided with a thermostat O . This as illustrated is composed of a coil o wound about the horn and filled with a liquid which boils at a low temperature and for which purpose alcohol or ethyl chlorid are frequently employed. A perforated screen o^1 surrounds the said thermostat O to admit atmospheric air and render the same quickly responsive to changes in temperature. The drip pipe N has openings n by which the thermostat is exposed to the 80 temperature of the escaping fluid within the drip pipe N . The upper end of this coil o is connected by tube o^2 to a thermostatic chamber o^2 having the usual diaphragm o^3 which bears upon the head of valve stem o^4 , 90 and closes the valve P in the steam supply pipe A^1 when the chamber o^2 is expanded. A spring p maintains this valve normally open, and the thermostat O operates to close the valve against the pressure of this spring. 95 It will now be seen that upon the raising of the valve k^3 the condensed water and steam from the return pipes will be permitted to escape through ports k^8 k^7 which are then uncovered by the valve k^3 , and to pass through outlet k^8 and out through the drip pipe N , and that the temperature of the said 100 escaping water or steam will affect the thermostat O and through it control the valve P . Therefore when steam is escaping from the said return pipes through the common outlet k^8 the valve P will be closed, shutting off the supply of steam to each of the radiators C C^1 or to such of them as may be then in operation, and when the temperature of the water of condensation passing through the drip N is sufficiently low to permit the contraction of the chamber o^2 , the spring p will open the valve P and an additional supply of steam will be permitted to flow into the radiators C C^1 . The radiating systems C C^1 have no communication with the atmosphere save through the traps L and M when the system is operating as a pressure system, or through said traps and the drip N when the system is operating as a vapor system, and the only connection which the said return pipes have with one another is through the valve K when the valve plug k^3 is raised. Therefore should it be desired to 110 reduce the supply of heat in the car, and for this purpose one of the valves c be closed, steam will not have access to the said closed radiating system.

115 The valve K illustrated in Figs. 3, 4 and 120

5 is not claimed herein, but is claimed in another application, filed by me on January 3, 1912, Serial No. 669,270.

It is not to be inferred from the particularity with which I have described the details of construction that I regard my invention as necessarily limited thereto, as the precise form, location and construction of the elements described may be changed and 10 equivalent devices substituted within the limits of the appended claims. Nor is my invention limited to the employment of the thermostat upon the drip pipe N, as this may be otherwise located without departing 15 from the invention.

I claim as my invention:—

1. A steam heating system having a plurality of radiating systems, a common supply pipe for all said systems, an automatic supply valve in said supply pipe, each of said systems having independent return pipes, an independent thermostatically controlled trap in each return pipe, and a common outlet for said system to which each return pipe is connected, and a valve in said common outlet for establishing communication from each return pipe to said common outlet, and thermostatically controlled means operated by the temperature in said 30 common outlet for controlling said supply valve.

2. A steam heating system embodying a plurality of radiating systems, a common supply pipe for said radiating systems, an independent return pipe for each radiating system, a multiple valve to which each return pipe is connected having an independent trap controlled outlet for each return pipe and having a valve controlled common outlet, an automatic valve in said supply pipe, and thermostatic means in said common outlet for controlling said automatic valve.

3. A steam heating system embodying a plurality of radiating systems, a valve in each system for shutting off the supply of steam to said system, a common supply pipe for said radiating systems, an independent return pipe for each radiating system, a multiple valve to which each return pipe is connected having an independent trap controlled outlet for each return pipe and having a valve controlled common outlet, each of said radiating systems being open 55 to the atmosphere only through said multiple valve, an automatic valve in said supply pipe, and thermostatic means in said common outlet for controlling said automatic valve.

4. A steam heating system embodying a plurality of radiating systems, a common supply pipe for said radiating systems, an independent return pipe for each radiating system, a valve body, a plurality of traps connected thereto, said valve body having

a plurality of passages therein, each passage connecting a return pipe to a trap, a valve controlling an outlet from said valve body, adapted when raised to connect each return pipe with said outlet, an automatic supply valve in said supply pipe, and thermostatically operated means for closing said supply valve controlled by the temperature in said outlet.

5. A steam heating system embodying a plurality of radiating systems, a common supply pipe for said radiating systems, an independent return pipe for each radiating system, a valve body, a plurality of traps connected thereto, said valve body having a plurality of passages therein, each passage connecting a return pipe to a trap, a gravity trap connected to each passage, a valve controlling an outlet from said valve body adapted when raised to connect each return pipe with said outlet, an automatic supply valve in said supply pipe, and thermostatically operated means for closing said supply valve controlled by the temperature in said outlet.

6. A steam heating system embodying a plurality of radiating systems, a common supply pipe for said radiating systems, a valve in each radiating system for shutting off the supply of steam to said system, an independent return pipe for each radiating system, a valve body, a plurality of traps connected thereto, said valve body having a plurality of passages therein, each passage connecting a return pipe to a trap, a valve controlling an outlet from said valve body adapted when raised to connect each return pipe with said outlet, and each of said radiating systems being open to the atmosphere only through said valve body, an automatic supply valve in said supply pipe, and thermostatically operated means for closing said supply valve controlled by the temperature in said outlet.

7. A steam heating system embodying a plurality of radiating systems, a common supply pipe for said radiating systems, an automatic supply valve in said supply pipe, an independent return pipe for each radiating system, a hand operated valve in each radiating system for shutting off the supply of steam to said systems respectively, a common valve to which each return pipe is connected, a plurality of traps connected thereto, said common valve having a plurality of independent passages, each passage connecting a return pipe to a trap, and having a common outlet communicating with each of said passages, a hand operated valve controlling said common outlet, and thermostatically operated means controlled by the temperature in said outlet for controlling said supply valve.

8. A steam heating system embodying a plurality of radiating systems, a common

- supply pipe for said radiating systems, an automatic supply valve in said supply pipe, an independent return pipe for each radiating system, a hand operated valve in each 5 radiating system for shutting off the supply of steam to said systems respectively, a common valve to which each return pipe is connected, a plurality of traps connected thereto, said common valve having a plurality 10 of independent passages, each passage connecting a return pipe to a trap, a gravity trap connected with each passage, said common valve having a common outlet communicating with each of said passages, a 15 hand-operated valve controlling said common outlet, and thermostatically operated means controlled by the temperature in said outlet for controlling said automatic supply valve.
- 20 9. A steam heating system having a plurality of radiating systems, a common supply pipe for all said systems, an automatic supply valve in said supply pipe, each of said systems having an independent return 25 pipe, each system having an individual outlet and all said systems having a common outlet, adjustable means adapted to connect each of said systems with said common outlet, means at each of said individual outlets 30 for controlling the same, thermostatically operated means controlled by the temperature in said common outlet for controlling said automatic supply valve, and an individual valve in each radiating system adapted when 35 closed to shut off the supply of steam to said system to close said system against the circulation of steam therethrough.
10. A steam heating system having a plurality of radiating systems, a common 40 supply pipe for all said systems, an automatic supply valve in said supply pipe, each of said systems having an independent return pipe, each system having an individual outlet, thermostatic means at each individual 45 outlet controlled by the temperature in said outlet and adapted to close same, and all said systems having a common outlet, adjustable means adapted to open and close
- communication between each of said systems and said common outlet according to 50 adjustment, and thermostatically operated means controlled by the temperature in said common outlet for controlling said automatic supply valve.
11. A steam heating system having a plurality of radiating systems, a common supply pipe for all said systems, an automatic supply valve in said supply pipe, each of said systems having an independent return pipe, each system having an individual 60 outlet and all said systems having a common outlet, a single valve adapted to open and close communication between each of said systems and said common outlet according to adjustment, means at each of said individual outlets for controlling the same, thermostatically operated means controlled by the temperature in said common outlet for controlling said automatic supply valve, and an individual valve in each radiating system 65 adapted when closed to shut off the supply of steam to said system to close said system against the circulation of steam therethrough.
12. In a steam heating system, a plurality 70 of radiators, a valve connected with each radiator adapted to shut off or admit fluid to the same, said radiators being provided with a common outlet and with an individual outlet for each radiator, a valve 75 adapted to control communication between each of said radiators and said common outlet, and a single thermostatic device to regulate the flow of fluid to all such radiators as are in operation, such thermostatic 80 device being responsive to thermostatic conditions at such common outlet and means at each individual outlet for controlling the same.
